UNITED STATES PATENT OFFICE.

MALCOLM D. McMILLAN, OF MARCY, MINNESOTA.

MAIL-BOX.

1,360,964.

Specification of Letters Patent. Patented Nov. 30, 1920.

Application filed April 12, 1919. Serial No. 289,574.

To all whom it may concern:

Be it known that I, MALCOLM D. McMILLAN, a citizen of Canada, residing at Marcy, in the county of Lake and State of Minnesota, have invented certain new and useful Improvements in Mail-Boxes, of which the following is a specification.

The present invention comprehends generally improvements in that class of inventions known as deposit and collecting receptacles and more particularly relates to an improved mail box.

It is the primary aim and object of this invention to provide a device of the above mentioned character of that type which are stationed along a rural delivery route and situated a considerable distance from the house of the owner thereof and designed to indicate as by an alarm and the signal of the presence of mail in the box.

As an additional and equally important object this invention contemplates the provision of a device of the above mentioned character wherein electrical contacts are operably mounted in the body of the box and normally arranged in an inactive position but upon the placing of mail in the box the contacts are designed to close the circuit of which a bell positioned in the house forms a part, thereby ringing the bell and indicating to the people in the house of the presence of mail in the box.

More particularly the present invention contemplates the provision of a device of the above mentioned character provided with a false bottom carrying a contact and which is operably connected with the indicating flag so as to be held in a raised non-indicating position by the resilient means which holds the flag while coacting therewith is a weight which is operably connected to the door and normally arranged through slots in the false bottom to contact with the main bottom when there is no mail in the box but upon the placing of mail in the box between the weight and bottom the weight is designed to simultaneously close the circuit and sound the alarm and move the indicating flag against the tension of the resilient means into an upright indicating position.

Among the other aims and objects of this invention may be recited the provision of a device of the above mentioned character wherein the number of parts are compara-

tively few, the construction simple, the cost 55 of production low and the efficiency high.

Other objects, as well as the nature, characteristic features and scope of this invention will be more readily apparent from the following description taken in connection 60 with the accompanying drawings and pointed out in the claims, forming a part of this specification.

The invention is clearly illustrated in the accompanying drawings, in which:— 65

Figure 1 is a horizontal sectional view of the invention,

Fig. 2 is a vertical longitudinal sectional view of the invention,

Fig. 3 is a vertical transverse sectional 70 view of the improved mail box, and

Fig. 4 is a perspective detail of the false bottom or contact plates.

Similar characters of reference are employed in all of the above described views. 75 to indicate corresponding parts.

Referring now, more particularly, to the accompanying drawings there is provided an improved mail box consisting of a substantially rectangular body 1 the front end 80 of which is open and is removably closed by a door 2 swingably connected to one edge of one of the side walls as by hinges 3 and removably held in such closed position by fastening means such as a hasp 4 which is 85 movably connected to the door as at 5 designed for engagement with a keeper 6 carried by the adjacent end of the other side of the body. The bottom of the body is provided medially of its ends and sides with a longitudinal slot 7 while the under surface 90 is provided with a transverse recess 8 which intersects the slot while anchored in this recess is a leaf spring contact 9 held by a suitable fastener 10. In addition, the under 95 surface of the body is provided with a cover plate 11 rigidly secured thereto and having the leaf contact in yielding engagement therewith as indicated in Fig. 3.

The inner surfaces of the side walls of the 100 body 1 are provided with opposed vertically disposed and relatively wide recesses 12 covered by guides 13 in the form of vertically disposed plates 14 provided with opposed vertical slots 15, the plates or guides being 105 anchored as by a fastener 16. In addition, these plates are provided at their lower edges on opposite sides of the slots 15 with rela-

tively short vertical slots 17, for a purpose that will hereinafter appear.

Movably mounted above the upper surface of the bottom of the body is the improved 5 false bottom or contact plate indicated in its entirety by the numeral 18 formed desirably of metal and of a rectangular configuration and provided near its end edges and medially of its ends with transverse slots 19. An 10 open rectangular frame 20 is carried transversely of the under surface of the plate 18, the side bars of the frame extending beyond the side edges of the plate and arranged in the recesses 12 and in the slots 17 in the 15 guides 13, the end bars 21 of the plate being arranged in a substantially inverted V-form in elevation and have connected thereto the lower ends of suitable flexible elements such as cables 22. The upper ends of these cables 20 are connected to and windable partially about spaced drums 23 in turn carried by a transverse shaft 24 the ends of which are journaled in the sides of the body near the top as indicated in the drawings.

The improved indicating means in the present instance consists of a flag 25 the staff 26 of which fastens as at 27 to one projecting end of the shaft 24. Now in order to normally hold the flag in a non-indicating 30 position, suitable resilient means such as coiled contractile spring 28 is employed, the respective ends being secured to the body and to the flag staff tensioned to normally hold the flag staff in a horizontal position 35 and inasmuch as this flag staff is connected to the shaft 24, the upper portions of the cable 22 will be held partly wound about the drum 23 and in consequence will maintain the false bottom or contact plate 18 in a 40 raised position, the upward movement of which is limited by the adjusting portions of the side bars contacting with the upper ends of the slots 17. The frame mentioned carries a U-shaped contact 29 which of 45 course is normally held raised and is designed to coact with the leaf spring contact 9 for the closing the circuit and the sounding of an alarm in a manner that will hereinafter become apparent.

Cooperating with the secondary bottom or contact plate 18 is a weight generally indicated by the numeral 30 the bottom being in a substantially rectangular plate-like form and fitted transversely at its under 55 surface and near its respective ends and medially of its ends with U-shaped supports or legs 31 designed to register with the transverse slots 19 so as to pass therethrough and contact with the main bottom of the box for 60 supporting of the weight in an elevated position. Opposed tongues 32 project from the opposite side edges of the plate-like body of the weight and are operably arranged in the slots 15 in the guides 13. Now, when 65 operably connecting the weight with the

door so that the weight will be raised upon the opening of the door, suitable flexible means in the form of a cable 33 is employed, the main portion being trained about a pulley 34 which is operably mounted in a depending bracket 35 on the top of the body, one end of the cable being connected as at 36 to the door while the opposite end is branched as at 37 and these branches are connected as at 38 to the upper surface of 75 the body of the weight 30 and by this arrangement it is apparent that when the door is moved to an open position a pull will be exerted on the cable 33 so as to in consequence raise the weight 30 upwardly from 80 the false or contact plate 18, the upward movement being guided by the tongues 32 which operate in the slots 15.

The circuit mentioned preferably consists of conducting wires 39 in which are interposed an alarm such as a bell 40 and a suitable source of energy such as batteries 41, the bell and batteries being mounted or positioned in the house while the conducting wires 39 are grounded as at 42 and 43 respectively to the contact plate 18 and to the bottom 11 and consequently the spring contact 9. When the box is empty, the weight 30 is supported in an elevated position above the bottom of the box upon the legs 31 which 90 extend through the slots 19, thereby permitting the plate 18 to remain in such elevated position to which it is elevated by the spring 28 acting to turn the shaft 24 and wind the cables 22 thereon. In this elevated position, 100 the contact member 29 is retained in spaced relation to the contact member 9 and the electrical circuit to the alarm device 40 is broken.

The mode of operation of the present invention may be reviewed as follows:

Assuming that the parts have been assembled in the manner described and as indicated in the drawings, the mail man upon opening the door 2 raises the weight 30 110 since the latter is connected with the door by the cable 33. The mail such as a letter 44 now is placed beneath the weight and on the contact plate or secondary bottom 19 and when the door is closed, the weight 30 115 will of course move downwardly but by reason of the fact that the letter or mail 44 lies across the slot 19 in the plate 18, the legs or support 31 will be prevented from contacting with the upper surface of the main 120 bottom of the body 1 but on the other hand the weight will act to move the plate 18 downwardly unwinding the cable 22 from the drum 23 thereby rocking or partially rotating the shaft 24 and raising the flag 125 staff 26 against the tension of the spring 28 also causing the contact 29 to engage the leaf spring contact 9 and close the circuit and in consequence sound the alarm such as a bell 40 in the house indicating to the peo- 130.

ple in the house of the presence of mail in the box. Incidentally, the flag staff being in a vertical indicating position will indicate to a person not in the house of the 5 presence of mail.

It is believed in view of the foregoing description that a further detailed description of the operation of the invention is entirely unnecessary. Likewise, it is believed that 10 the advantages of the invention will be readily apparent.

Still further embodiments of the invention than those herein especially defined may be resorted to as conditions or preference 15 may dictate, as may be in keeping with the hereto appended claims.

Having thus fully described the invention, what is claimed as new and desired to be secured by Letters Patent, is:—

20 1. A mail box including a body, an electrical contact carried thereby, a secondary bottom plate having a contact thereon and provided with slots, resilient means for normally holding the bottom plate above the 25 bottom of the body, and a weight composed of a body and supports depending therefrom and normally disposed through the slots and contacting with the bottom.

2. A mail box including a body having an 30 electrical contact on the bottom thereof, a plate serving as an electrical contact and a mail receiver yieldingly mounted in spaced relation to the bottom of the body, and a weight having supports depending therefrom and normally arranged through the 35 plate when no mail is on the plate but acting against mail which is adapted to be disposed on the plate to force the plate downwardly and cause the contacts to engage 40 each other.

3. A mail box including a body, a door 45 movably connected thereto, an electrical contact carried by the bottom of the body, a movable contact member arranged above the bottom of the body and having slots therein, resilient means for normally holding the movable member in a raised position, a weight lying over the movable member and having depending supports normally arranged through the slots in the 50 movable member and contacting with the bottom of the body, and flexible connection means between the weight and the door for raising the weight upon the opening of the 55 door so that mail may be inserted between the movable member and the weight to prevent contact of the weight with the bottom

of the body and in consequence cause the member to move downwardly to engage the contact on the bottom of the body. 60

4. A mail box including a body, a door movably connected thereto, a contact carried by the bottom of the body, a movable contact member arranged above the bottom of the body and having slots therein, a pivoted indicator on the body and operably connected with the movable contact member, resilient means for normally holding the indicator in a non-indicating position and the movable member in a raised position, a 70 weight lying over the movable member and having depending supports normally arranged through the slots on the movable member and contacting with the bottom of the body, flexible connecting means between 75 the weight and the door for raising the weight upon the opening of the door so that mail may be inserted between the movable member and the weight to prevent contact of the weight with the bottom of the body 80 and in consequence cause the member to move downwardly and engage the contact on the bottom of the body and also raise the indicator against the tension of the resilient means. 85

5. A mail box including a body, an article supporting plate yieldably supported in an elevated position therein, relatively stationary and movable circuit closing members carried by the body and plate, respectively, 90 and a weight arranged to be normally supported upon the body independently of the plate and adapted, upon application of an article to the plate, to exert pressure thereon and effect contact of the circuit closing 95 members.

6. A mail box comprising a body, an article supporting plate yieldably supported in an elevated position, relatively stationary and movable circuit closing members carried by the body and plate, respectively, 100 a weight arranged to be normally supported upon the body independently of the plate, and adapted, upon application of an article to the plate, to exert pressure thereon and effect contact of the circuit closing members, a door for said body, and means connecting said door with the weight whereby the latter is elevated upon opening of the 105 door. 110

In testimony whereof I affix my signature hereto.

MALCOLM D. McMILLAN.
